LOCK

Charles K. Ernst, Buffalo, N. Y.

Application December 18, 1934, Serial No. 758,048

5 Claims. (Cl. 70—31)

This invention relates to improvements in safes in which valuables may be protected from fire and theft.

The objects of this invention are to provide a safe of this kind with means for preventing the blowing up of the safe by means of a liquid explosive; also to provide a safe with a dial or lock operating device which may be removed from the safe, and in which means are provided to close or stop the hole or passage through which the lock operating device actuates the lock, so that the insertion of other lock operating means through the hole or passage is prevented; also to provide a safe in which an outer closing device is provided which must be opened by means of a key or other unlocking means before the main lock of the safe is rendered accessible and to so construct the safe that the breaking of the lock for the outer closing device will not result in the opening of this device; also to provide a safe in which the main lock comprises a plurality of bolts actuated from a single locking device; also to provide a safe of this kind which may be secured to a floor or foundation of a building in which it is located so that it cannot be detached from the floor without first opening the safe; also to provide a safe of the kind having a small tube, through which valuables may be deposited in the safe without opening the safe, with means for locking said tube to prevent access to the valuables compartment therethrough; also to provide a safe of this kind with a wall having a space formed therein filled with a substance which, when exposed, will produce fumes such as to repel the thief or thieves; also to improve the construction of safes of this kind in other respects hereinafter specified.

In the accompanying drawings:

Fig. 1 is a perspective view of a safe embodying this invention.

Fig. 2 is a top plan view thereof on an enlarged scale and with the outer locking device removed.

Fig. 3 is a vertical central sectional elevation thereof.

Fig. 4 is a fragmentary sectional elevation on a still larger scale on line 4—4, Fig. 3.

Fig. 5 is a side elevation of the removable member of the safe showing partly in section the means for closing the tube through which valuables may be deposited in the safe while the same is locked.

Figs. 6 and 7 are sectional plan views, on line 7—7, Fig. 9, with certain parts in different positions, and with the detachable member of the column lock actuating means omitted in Fig. 6.

Fig. 8 is a perspective view of the column lock actuating device of the safe.

Fig. 9 is an elevation, partly in section, showing the lock actuating device being positioned into its operative relation to the removable column of the safe.

Fig. 10 is a fragmentary sectional elevation of the portion of the column on which the lock is mounted.

Fig. 11 is a sectional plan view thereof, on line 11—11, Fig. 10.

Fig. 12 is a similar view showing the parts in different positions.

Fig. 13 is a fragmentary sectional elevation on an enlarged scale showing a plunger for moving the outer locking means of the safe into open position when unlocked.

Fig. 14 is a sectional elevation of a sump or receptacle into which liquid explosive may flow, and which is adjacent to a weakened portion of the outer wall of the safe.

Fig. 15 is a fragmentary central sectional elevation of the middle portion of the removable member or column of the safe, showing the connection between the locking device and the actuating mechanism therefor.

Fig. 16 is a fragmentary sectional elevation on an enlarged scale, on line 16—16, Fig. 3.

Fig. 17 is a fragmentary sectional elevation thereof on line 17—17, Fig. 16.

The safe forming the subject matter of this application is of a type similar to that shown in my Patents Nos. 1,954,667 and 1,954,668, but in the particular form shown, the safe, instead of being arranged in the ground or below a cellar or foundation floor, or in a mass of concrete arranged within a building, is of a more or less portable type including an outer housing or shell 15 within which is contained a mass of solid material, such as concrete 16 which may be reinforced in any suitable or desired manner by metallic reinforcing members 17 or the like. Although my improvements are shown as applied in a portable type of safe, it will be understood that certain of these improvements may, nevertheless, be applied equally well to safes of the kind arranged in the ground or permanently installed in building structures.

The safe shown also includes the usual inner space for valuables, which may have a lining or shell 18, and which preferably terminates near its upper end in an enlarged space 19 within which a locking or lock actuating device for the valuables compartment is located, and in which some valuables may also be stored. This en-

30

35

40

45

50

55

larged space or compartment 19 is provided with a bottom wall 20 and upright or side walls 21 terminating at the upper plate or head 22 of the safe. A similar plate 23 may be used at the lower end of the safe. 25 represents the removable inner member or column of the safe which is slidable into and out of the inner space of the safe, and which may be locked to a stationary or fixed portion of the safe in any suitable manner. A valuables compartment 27 may be secured to the lower end of this removable member or column 25, or the valuables compartment may be separate from the column so as to be removable by means of a rod or hook, or if desired, a plurality of valuables compartments may be provided, as shown in my Patent No. 1,954,668. In the particular construction shown, the valuables compartment is provided with a hole or aperture 28 in the side thereof and a circuitous drop tube or duct 29 preferably terminates at its lower end opposite this opening while the upper end of this tube terminates in an aperture in the base plate 20 of the compartment 19. It will, of course, be understood that if desired this tube may be entirely omitted.

The upper compartment 19 of the safe is preferably closed by means of a closing device which is so formed as to prevent the dropping or pouring of liquid explosive, such for example as nitroglycerine, into the interior of the safe, through crevices or openings in the safe. Any suitable device may be employed for this purpose, and in the construction shown a closing plate, door or slide 31 is provided which preferably has a close fit with the top plate 22 of the safe, and which is provided at its sides with channelled or grooved edges 32 which interfit with correspondingly shaped tongues in the top plate 22. This arrangement, if the tongues or grooves interfit snugly, will prevent liquid explosive from flowing from the top of the plate into the interior of the outer compartment 19, and if the tongues and grooves fit loosely, as will happen if the slide has become worn, then the troughs or grooves will conduct the liquid to the front ends thereof, from where it will be discharged on the outside of the safe, so that the ignition of such explosive will not open the safe. The inner end of the closing slide 31 preferably has a rabbeted fit with the top plate 22 of the safe and the front or outer edge of the slide 31 extends over the wall of the safe to such an extent that liquid cannot be poured through the horizontal space between the slide and the safe wall. Any other means for preventing the pouring of liquid explosive into the compartment 19 or into the interior of the safe may be provided, if desired.

The slide 31 is preferably held in closed position by means of a locking device operable by a key or a tumbler operated combination lock. In the construction shown, a key operated lock 35 is illustrated, which may be of any suitable or usual construction, and which is arranged within the space 19 in the upper end of the safe. The key (not shown) for the lock may be inserted into a tubular extension 36 of the lock to actuate this lock in the usual manner. In order, however, to prevent damage to the lock from enabling a thief to obtain access to the compartment 19, I preferably arrange the lock so that it actuates a second locking member which is removably connected with the lock so that the breaking of the lock or the driving 75 of the lock inwardly by blows on the tubular

part 36 will not release the closing plate or slide 31. In the construction shown for this purpose a vertically slidable locking bolt or plate 38 is provided which extends substantially throughout the width of the compartment 19 and the opposite sides of which are slidably arranged in guides 39. The locking slide 38 is adapted to extend into a recess 40 arranged near the front edge of the slide 31 and extending substantially throughout the width of the same, thus forming a very secure lock for the slide and which prevents any implement from being inserted between the front end of the slide 31 and the outer wall of the safe. The locking bolt 38 is preferably urged upwardly into its locking position independently of the lock 35, and in the construction shown for this purpose, springs 41 are shown, the upper ends of which engage the locking bolt 38 and the lower ends of which bear on brackets or supports 42 suitably arranged within the compartment 19. The lock 35 has a bolt 43 which may be connected with the main locking bolt 38 in any suitable or desired manner, and in the construction shown, the upper end of this bolt is of dove-tailed form and fits into a corresponding recess in the locking slide 38 so that the locking slide and the bolt 43 will move up and down together. Consequently, if the lock is driven inwardly by blows on the tubular portion 36 thereof, the dove-tailed portion 43 will move out of engagement with the corresponding part of the main bolt 38 without releasing this bolt from its locking position. It will also be noted that any other damage to the lock will not release the bolt 38 from its locking position, in which it is held independently of the lock.

Since the outer surfaces of the closing slide 31 for the compartment 19 are preferably entirely smooth and without a handle or other means for moving it into an open position, means are preferably provided for moving this closing slide into open position when released by the bolt 38. In the construction shown for this purpose, see Figs. 3 and 13, a spring pressed plunger 45 is provided which is pressed outwardly by means of a spring 46 and engages a portion of the closing slide 31, such for example as a screw or projection 47 secured thereto. When the closing slide is pushed into its closing position, the spring 46 will be compressed and at the same time the bolt 38, which is continuously urged against the undersurface of the closing slide 31, will enter into the recess 40. When the compartment 19 is unlocked by withdrawing the bolt 38, the spring 46 will press the plunger 45 outwardly to move the slide a short distance in an opening direction, whereupon the slot 40 in the undersurface of the slide will be accessible for pulling the closing slide into wide open position. Since the bolt 38 engages the closing slide substantially across its entire width, a very secure locking of the slide is assured and since the spring 46 urges the slide outwardly or forwardly, this spring will also urge the bolt into contact with the front wall 21 of the compartment 19 of the safe, so that the pouring of liquid explosive through the slit or space between the slide and the wall of the safe will be further prevented by the tight fit of the bolt 38 against the wall 21. Yielding means other than the spring 46 and plunger 45 may, of course, be provided for urging the closing slide 31 into open position, and if desired, two or more of such yielding devices may be employed.

The closing slide may be of any suitable or desired material but is preferably made of laminated metal, the successive laminations of which are of hard and soft materials, such as hardened 5 steel and a soft steel or iron, so that drilling or cutting through this slide is rendered extremely difficult. A slide of other material may, of course, be provided, if desired. The screw 47 also acts as a stop to hold the slide 31 against being entirely withdrawn from the safe, but if desired, the screw may be removed to permit the complete withdrawal of the slide from the safe.

The removable inner member or column 25 of the safe is preferably constructed substantially 15 as shown in my earlier patents above referred to and includes a plurality of horizontal plates 50 spaced apart by cylindrical spacing members 51 and suitably connected by upright members, such as angle bars 52, which may be arranged 20 at the four corners of the horizontal plates 50. The removable member may be provided at the upper portion thereof, which is located in the compartment 19, with a suitable dial 53 or other means for actuating a lock, and the lock is 25 preferably arranged at a considerable distance below the upper end of the removable member. In the particular construction shown, the lock is arranged below one of the horizontal plates 30 50 of the inner member and includes the usual housing 54 within which the tumblers or other operating parts (not shown) of the lock may be arranged and from which a locking bolt 55 extends outwardly preferably through a hole or recess in the lining member 18 for locking the 35 inner member of the safe to the housing thereof. Movement may be imparted to the tumblers from the dial by means of a shaft or rod contained within a tube 56 extending through the horizontal plates 50 to the housing 54 of the 40 lock and the actuation of the tumblers in the housing 54 also results in actuation of the bolts 55.

In order to more securely lock the inner or removable member of the safe, additional bolts 45 are preferably provided which may also be shifted by means of the bolt or other movable member 55 of the lock. For this purpose, in the construction shown, I provide a short tube or pipe 58 suitably secured to the inner or removable member 50 and extending horizontally crosswise of the same and provided with cylindrical locking bolts 59 arranged in the opposite end portions of the tube. These bolts are movable inwardly and outwardly with respect to the tube and through 55 apertures 60 in the lining member 18 of the safe. The bolts preferably have longitudinal slots formed in the inner portions thereof, as indicated at 61, see Figs. 10 to 12 inclusive, and the tube 58 is provided with a corresponding slot 62. The locking bolts 59 may be moved inwardly or outwardly by any suitable means connected with the bolt 55, or other movable member of the lock, and in the construction shown, I provide a connecting slide member having one 65 end connected with the bolt 55, for example, by means of a pin or post 63. The connecting member, as shown, is bifurcated, having its legs 64 straddling the central tube 56 of the inner removable member or column, and the legs 64 also 70 extend through the slots 62 of the tube 58 and the slots 61 of the locking bolts 59. Each of these legs is provided with an inclined slot 65 and each bolt 58 has an upright pin 66 secured thereto and extending through the slot 61 of the bolt and 75 through the inclined slot 65 of the corresponding

leg of the connecting member. Consequently, if the bolt 55 is moved to the right in Figs. 11 and 12, the bifurcated member will also move in a similar manner, thus causing the bolts 59 to move outwardly into locking positions as shown 5 in Fig. 11, while movement of the connecting member in the opposite direction will draw the bolts 59 inwardly into their unlocked positions, as shown in Fig. 12. As a result of this construction, the column of the safe is locked at three 10 different places, and the bolts 59 may be of very sturdy construction so as to securely lock the column in the safe. Any other means for actuating additional bolts from the lock of the safe may, of course, be employed if desired. 15

The lock within the lock housing 54 may be actuated by any suitable or desired means, such for example as a key, on an elongated handle which may extend downwardly through the tube 56, as shown and described in my Patent No. 1,954,668. A dial may be employed for actuating the lock, the dial being preferably located in the compartment 19 of the safe, and in cases where the lock is mounted on the column, the dial is preferably also mounted on the upper end of the 20 column. It will be understood, of course, that the column lock may be secured on a fixed part of the safe on the exterior of the column, the arrangement of the lock on the column as shown 25 in the drawings, being, however, preferred because of the convenience of making adjustments or repairs on the lock. If a dial is used, the dial is preferably made removable so that it can be concealed or carried to another location when 30 the safe is locked. The dial, whether removable or fixed, preferably connects with the main or column lock through a rod extending through the tube 56. This rod is preferably made in several sections, one section 70 being directly connected with the locking mechanism within the 35 housing 54 and the other section 71 is connected with the rotatable knob 72 of the dial 52. A third or intermediate section 73 of the rod is 40 preferably arranged within the tube 56 to connect with both the sections 70 and 71 in any suitable manner. For example, the connecting ends of the sections may be notched or rabbeted, as 45 shown in Figs. 8 and 15, so that an easy interfitting of the sections results. The intermediate section may, of course, be omitted, if desired. 50 Consequently, if an attempt on the part of thieves to unlock the column results in damage to the intermediate section, this section may later be removed and replaced by a similar part. 55

The dial 52 and its base portion 71 on which it is rotatably mounted may be constructed in any suitable manner so as to be removed from the safe. In order to enable the base 71 and the dial 52 to be correctly positioned relatively to the lock, the base is provided with one or more downwardly extending posts or pins 78, 79 and 80, which are adapted to enter into apertures formed in the top or cover plate 81 of the column. The upper section 71 of the rod is preferably 60 arranged in a short tube or guide part 82 secured to the base 71 and extends into position to connect with the intermediate section 73 of the actuating rod for the lock. Consequently, when the dial is in operative position, the lock may be 65 actuated to draw the bolts 59 and 55 inwardly to unlock the column or to move the bolts into their locking positions, and when placing the dial into its operative position, it is necessary to 70 turn the knob 72 thereof so that the upper 75

section 71 may move into correct gripping relation to the intermediate section 73 of the rod.

Means are preferably provided for closing or intercepting the tube 56 or passage when the dial is removed for preventing a thief from getting access to the actuating rod for the column lock. Any suitable or desired means may be employed for this purpose, and in the construction illustrated, there is provided between the upper transverse protecting plate 50 of the column and the top plate 81 thereof, a movable transverse plate 90 pivoted at 91 on the plate 50 and adapted to move over the upper end of the tube 56 containing the lock actuating rod. Immediately above the pivoted plate 90 is a short section 92 of tubing which is secured to the top plate 81 of the column, and the lower end of which is arranged in alinement with the tube 56 but spaced from the upper end of this tube at a distance sufficient to allow the plate 90 to swing between the tubes 92 and 56. The plate 90 is arranged to swing into tube closing position when the dial is removed from the safe and into opening position when the dial is inserted into its operative position on the safe. Any suitable means for accomplishing this result may be employed in the construction illustrated. The plate is yieldingly urged into closing position and is moved into opening position by a part of the dial. This may be accomplished by means of a spring 93 secured at one end to a plate 50 of the column and at its other end to the swinging plate 90 so as to normally swing this plate into a position across the tube 56 and into contact with a stop 94 suitably secured to the plate 50. The swinging plate 90 also has on one end thereof an upwardly extending projection 95 having an upper inclined or bevelled face 96. The pin or rod 78 extending downwardly from the base of the dial is adapted to engage the inclined face 95 when the dial is moved into its operative position, and for this purpose may be provided with a corresponding bevel or inclination 97 on the lower face thereof. By means of the engagement of the inclined or bevelled face 96 with the pin 78, a swinging of the plate 90 from the position shown in Fig. 6 to that shown in Fig. 7 results, thus utilizing the initial downward movement of the dial for swinging the plate 90 out of its tube closing position, while the remaining downward movement of the dial places the upper section 71 of the connecting rod between the dial and the lock into operative relation to another section of this rod.

During the use of the safe, it may be desired to lock the column and to drop valuables or packages from time to time into the valuables compartment through the drop tube 29, in which case the compartment 19 of the safe may be left unlocked, thus exposing the upper end of the drop tube. When the day's business is concluded, it is desirable to provide means for locking the drop tube as well as the compartment 19 of the safe, and in the construction shown for this purpose, a locking device is provided, which is mounted on the column, and which may be left in a position out of registration with the drop tube when the column is locked and later moved into position to lock or close the drop tube. In the construction shown for this purpose, the upper end of the column which projects above the bottom of the compartment 19 is provided with a projection 100 spaced from a projecting portion of a top plate 81 of the column and a movable tube closing device 101 is pivoted

on the projection 100 and top plate 81 in any suitable manner, for example, by means of a pivot pin 102. The closing device for the drop tube may, of course, be movably mounted on the column in any other manner. The outer portion of the closing member 101 is preferably made of inverted cup-shape or hollow cylindrical form and serves as a guide for a plunger 103 which may be moved up and down in this guide. A spring 104 may be provided for yieldingly urging the plunger 103 downwardly. The plunger is preferably of such size and shape as to enter into the upper end of the drop tube 29 when the closing device 101 is moved into a position in which the plunger 103 may move into the drop tube. When the column 25 of the safe is placed into the safe and locked, the plunger guide 101 may be moved toward one side of the drop tube 29, thus leaving the upper end of the drop tube exposed or open. The lower end of the plunger will then bear against the bottom plate 20 of the compartment 19 and the plunger will be telescoped into its guide. When it is desired to close the drop tube, the plunger guide or closing device is moved to position the plunger over the drop tube, whereupon the plunger will drop into the upper end of this tube. The plunger guide is preferably provided at the lower end thereof with a shoulder 106 adapted to cooperate with a shoulder 107 on the plunger 103 to limit the extent to which the plunger may move downwardly out of its guide.

When the drop tube closing device is moved into position to close the drop tube, it obviously cannot again be moved into opening position without unlocking the column 25 and moving the same outwardly to withdraw the plunger 103 out of the end of the drop tube.

The closing slide 31 of the outer compartment 19 of the safe is made to prevent the dropping of liquid explosives into the safe. Further precautions are preferably employed to prevent the blowing up of the safe if by any means a thief has succeeded in removing the closing slide 31, or if a robbery occurs while this slide is in its open position. For this purpose, I preferably provide means for draining liquid explosives from the middle portion of the safe to a portion near the outer wall thereof. Preferably the portion of the safe at the lower end of the lining member 18 is inclined or funnel-shaped to permit the liquid explosive to drain into a discharge pipe 110 which extends through the reinforced concrete surrounding the inner portion of the safe and which terminates in a receptacle or sump 111 preferably arranged adjacent to the outer wall 15 of the safe, as shown in Fig. 3. Consequently, if the explosive is ignited, the explosion will expend itself by blowing a portion of the outer wall outwardly but will not blow out the column 25 nor render the valuables compartment accessible. A portion of the outer wall immediately adjacent to the sump 111 may also be weakened in any suitable manner, for example, by means of an annular slot 112 extending partly through the outer wall 15, Fig. 14. Consequently, if liquid explosive is poured into the safe, it will drain into the sump 111 and if the explosive is ignited, the main charge will be exploded in the sump 111 which will result in blowing out the weakened portion of the outer wall 15 of the safe, and thus avoid damage to the main portion of the safe and avoid blowing the column 25 out of the safe. In order to permit any explosive discharged into the valuables compartment to be

partment to drain out of the same, the bottom of this compartment may be provided with one or more small holes or apertures 114. Other means for discharging liquid explosive from the interior 5 of the safe may be provided in place of those shown.

Means are preferably also provided for repelling thieves attempting to burn through the outer shell or housing of the safe by means of welding 10 or cutting flames or the like, and in the particular construction illustrated, I provide a layer of gas forming material, which is preferably embedded in the concrete or filling material arranged between the outer walls of the safe and 15 the lining member 18. In the particular construction shown, see Fig. 3, a pair of metal cylinders or containers 115 and 116 are provided, arranged one within the other and spaced apart to provide between them a space which may be 20 filled with such gas forming material. The cylinders or containers 115 and 116 may terminate at the walls of the compartment 19, but otherwise entirely surround the inner column and 25 valuables compartment of the safe. The protective gas forming material may be otherwise arranged in the wall of the safe and may either form a continuous layer around the column and valuables compartment, or may be so closely spaced as to prevent any one from gaining access 30 to the valuables compartment without encountering one or more masses of the gas forming material. Any suitable material may be employed which is capable of forming or liberating a gas which will repel thieves. For example, 35 sulphur may be employed, which will become ignited when a flame penetrates through the outer portions of the safe to a sufficient extent to contact with the sulphur. The fumes of sulphur dioxide thus formed will make it impossible for 40 a thief to continue in his attempts to gain access to the safe. Any other gas liberating substance may, of course, be employed in the space between the two cylinders 115 and 116, or otherwise arranged in the outer wall of the safe.

45 It is also desirable to provide means for preventing the carrying off of the safe, in case the same is of a portable type. This may be accomplished by means of the construction shown in Fig. 3, in which a bolt 120 may be arranged in 50 the floor of the building in which the safe is located, or which may be embedded in a concrete foundation or floor 121. The safe is provided in the lower portion thereof with an aperture through which this bolt may pass into the interior 55 of the safe below the valuables compartment 21, and the threaded part of this bolt is arranged to extend into the interior of the safe. A nut 122 may then be engaged with the threaded end of the bolt in the interior of the safe so as to secure the safe to the floor through the medium of the bolt 120. The nut 122 is, of course, only accessible if the safe is unlocked and the column 25 is removed therefrom. Consequently by means of this construction, the safe 60 may readily be removed by its owner, if desired, but removal by unauthorized persons is prevented.

125 represents a bail or handle which may be provided, if desired, to facilitate the removal of 70 the column from the safe. The bail, as shown, is pivoted on lugs or projections 126 secured to the top plate 81 of the column.

In order to foil any attempts that may be made to fish out valuables from the valuables 75 compartment of the safe by means of a flexible

wire or cord with hooks, adhesive or other appliances attached to the end thereof, in the event that the upper end of the circuitous drop tube 29 should be open and accessible, means are preferably provided for stripping such valuables from 5 such fishing appliance when it is attempted to draw such valuables out of the valuables compartment through the drop tube. Any suitable or desired means may be employed for this purpose, and in the construction shown, a series of 10 inwardly projecting teeth or pointed members 127 may be provided, see particularly Figs. 3, 16 and 17. These projections or teeth may be formed by bending portions of the metal of the side wall 128 of the valuables compartment inwardly and forming this metal into the shape of teeth or projections, preferably with sharp points so that they will engage any valuables that may adhere to the fishing implement and strip them from such implement and cause them 15 to drop back into the valuables compartment. Since these teeth or projections point downwardly and inwardly toward the interior and bottom of the valuables compartment, they will in no way interfere with the dropping of valuables from the 20 drop tube 29 into the valuables compartment.

It is also desirable to provide means for preventing the removal of valuables from the valuables compartment by a fishing implement and by floating the valuables to the top of the valuables compartment above the teeth or projections 127 so that these teeth will not engage the valuables when taken from the compartment to the drop tube by the fishing implement. This might, for example, be done by pouring water 30 into the valuables compartment through the drop tube 29, in which case such valuables as bills and other articles lighter than water would float to the top of the valuables compartment from which they might be readily removed by 35 the fishing implement. In order to prevent the removal of valuables in this manner, I preferably provide suitable float means actuated by liquid poured into the lower end of the safe, and which float means operate to intercept the drop tube 29. Any suitable or desired means may be employed for this purpose. In the construction shown, by way of illustration, I have provided a float 130, which is arranged adjacent to a side 40 of the inner lining member 18 of the safe, and 50 which is arranged in a guide or container 131 having an aperture 132 in the upper wall thereof through which a rod 133 extends. The lower end of the rod is preferably secured to the float 130 and the upper end may be arranged to extend 55 across the drop tube 29 when the float is raised by liquid poured into the safe. Any suitable means may be employed for this purpose. In the construction shown, the upper end of the rod 133 is forked, being provided with three prongs or 60 bars 134 which extend through apertures 135 in the drop tube. When the float is in lowered position as shown in Figs. 3 and 16, the upper ends of the prongs 134 of the fork are withdrawn 65 from the apertures 135 so as not to extend into the drop tube nor interfere in any way with the movement of valuables through the drop tube and, if desired, the apertures 135 may be provided with downwardly extending tubular projections 136. When liquid is poured into the safe the float 130 is raised so that the prongs 70 134 will extend upwardly across the drop tube 29, as shown in Fig. 17, thus barring the passage through the drop tube and preventing the re- 75

75

moval of valuables upwardly through the drop tube.

In order to permit water or other liquid to flow into the interior of the housing or guide 5 131 in which the float is contained, the valuables compartment may be provided with an aperture 137 registering with apertures 138 in the inner lining member 18 and the guide housing 131 for the float. Any other suitable or desired means 10 for closing or partly closing the drop when liquid is poured into the safe may be employed.

I claim as my invention:

1. A safe having a compartment, a closing member for said compartment having a slidable 15 connection with said safe and having a groove on the inner face thereof extending transversely of the direction of sliding movement of said closing member and substantially from side to side thereof, and a locking bolt in the form of 20 a substantially flat plate arranged in said outer compartment and adapted to be moved into said groove for locking said slidable member in closing position and located in contact with a wall of said outer compartment to prevent insertion 25 of anything between said slidable closing member and said wall.

2. A safe having a compartment closed by a member slidably arranged on a wall of the safe and having a groove on the inner face thereof 30 extending transversely of the direction of sliding movement of the closing member, a locking bolt in the form of a substantially flat plate arranged to move into said groove, means for yieldingly urging said bolt into locking position in 35 said groove, and a lock for moving said bolt out of said groove into opening position, against the action of said yielding means.

3. A safe having an outer wall provided with an opening therein, a closing device for said 40 opening and slidably arranged relatively to the outer wall of the safe and having its outer surface substantially flush with said outer wall and

having a slot extending into the inner surface thereof adjacent to the outer edge thereof, a bolt in the form of a plate extending substantially throughout the width of said closing device and arranged to extend into said slot, locking means for moving said bolt into unlocking position, and resilient means urging said bolt into locking position in said slot independently of said locking means. 5

4. In a safe having an opening in one wall adjacent to another wall, a slide for closing said opening and slidably mounted on said first mentioned wall and having a slot extending crosswise of the direction of sliding movement of said slide and arranged adjacent to said other wall, a 15 bolt in the form of a plate extending substantially throughout the width of said slide and movable in a direction substantially parallel to said other wall into and out of engagement with said slot to lock said slide, means for yieldingly urging said bolt into locking position, and a lock for actuating said bolt and detachably connected therewith, whereby, when said lock is moved from its operative position relatively to said bolt, the bolt will remain in locking position. 20 25

5. In a safe having an opening in one wall adjacent to another wall, a slide for closing said opening and slidably mounted on said first mentioned wall and having a slot extending crosswise of the direction of sliding movement of said slide and arranged adjacent to said other wall, a bolt in the form of a plate extending substantially throughout the width of said slide and movable in a direction substantially parallel to said other wall into and out of engagement 30 with said slot to lock said slide, and a lock for moving said bolt into locking position, said bolt extending across the space between said slide and said other wall to prevent the forcing of an implement through said space to pry off said slide. 35 40

CHARLES K. ERNST.
